Primary Examiner — Patricia A Palasik(74) *Attorney, Agent, or Firm* — Schwegman Lundberg & Woessner, P.A.(57) **CLAIM**

The ornamental design for an industrial robot, as shown and described.

DESCRIPTION

FIG. 1 is a front, top, and right side perspective view of our design for an industrial robot;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a front, top, and right side perspective view showing an arm of the article being stretched out; and, FIG. 9 is a rear, top, and left side perspective view showing an arm of the article being stretched out.

The broken lines illustrate portions of the industrial robot that form no part of the claimed design. The dash-dotted lines denote the boundary of the claim and form no part of the claimed design.

1 Claim, 9 Drawing Sheets(56)
